US00D540812S

(12) United States Design Patent (10) Patent No.: US D540,812 S
Gusmorino et al. (45) Date of Patent: * Apr. 17, 2007

(54) ICON FOR A PORTION OF A DISPLAY SCREEN

(75) Inventors: Paul Gusmorino, Seattle, WA (US); Mark R. Ligameri, Austin, TX (US); Jenny T. Lam, Seattle, WA (US); Greg S. Melander, Redmond, WA (US); Robert Kenneth Stein, III, Redmond, WA (US)

(73) Assignee: Microsoft Corporation, Redmond, WA (US)

() Term: 14 Years

(21) Appl. No.: 29/228,403

(22) Filed: Apr. 22, 2005

(51) LOC (8) Cl. 14-04

(52) U.S. Cl. D14/492

(58) Field of Classification Search D14/485-95; D18/32, 33; D19/6, 1; D20/11; D21/324, D21/329; 715/700-866

See application file for complete search history.

(57) CLAIM

The ornamental design for an icon for a portion of a display screen, as shown and described.

DESCRIPTION

The FIGURE is a front view of an icon for a portion of a display screen showing our new design.

The broken line showing of a portion of a display screen is for illustrative purposes only and forms no part of the claimed design.
